UNITED STATES PATENT OFFICE.

ALTON HUGH RAGSDALE, OF ATLANTA, GEORGIA.

INTERNAL-COMBUSTION ENGINE.

1,162,252.

Specification of Letters Patent. Patented Nov. 30, 1915.

Application filed September 16, 1913. Serial No. 790,034.

To all whom it may concern:

Be it known that I, ALTON H. RAGSDALE, citizen of the United States, residing at Atlanta, in the county of Fulton and State of Georgia, have invented certain new and useful Improvements in Internal-Combustion Engines, of which the following is a specification.

My invention relates to internal combustion engines, and particularly to engines of that type wherein reciprocating valve sleeves are used in place of puppet or like valves for controlling the inlet to and exhaust from the cylinders. The principal objection to this type of motor lies in the difficulty of keeping the valve sleeve cool and hence preventing it from binding, in securing a proper movement of the valve with a relatively short throw of the crank and in properly lubricating the valve.

The primary object of my invention is to so form the valve system of an internal combustion engine of this type as to remedy the above referred to defects and to secure simplicity of construction and operation.

Another object is to so arrange and construct the valves that they may operate in a valve chamber separate from the engine cylinders and whereby one valve may control the inlet of motive fluid to a plurality of cylinders and one valve control the outlet of the exhausted fluid from a plurality of cylinders.

Another object is to provide for lubricating the valves both by a splash from the crank case and by lubricant pumped from the case.

Another object is to so construct the valve sleeve that the power applied to shift it shall be applied at the axial center of the valve and not to one side thereof, thus reducing any tendency of the valve to bind.

A still further object is to provide improved means for shifting the valve sleeves to secure the movement of the sleeves with a relatively short throw of the crank on the valve shaft.

A still further object is to so construct the cylinder that it need not be removed from the crank case but that the cylinder head may be removed to permit renewal or repair of the piston, the replacement of packing or the cleaning of the cylinder.

A further object is to so construct the valve chamber that the head thereof may be readily removed whereby to permit the re-

moval or replacement of the valve and the cleaning of the valve chamber if necessary.

Other objects will appear in the course of the following description.

My invention is illustrated in the accompanying drawings wherein:

Figure 1 is a side elevation of two cylinders of an engine, the cylinders and the crank case being partially broken away in order to show the internal construction. Fig. 2 is a vertical section on the line 2—2 of Fig. 3 showing the internal construction of the valve chambers and the means whereby the valves are operated. Fig. 3 is a section on the line 3—3 of Fig. 2. Fig. 4 is a perspective detail view of the fixed valve sleeve or internal wall of the valve chamber. Fig. 5 is a perspective detail view of the sliding valve sleeve and the mechanism whereby it is operated. Fig. 6 is a detail view of the valve operating crank and the cam carried thereby. Fig. 7 is a perspective view of the eccentric yoke for operating the valve. Fig. 8 is an enlarged fragmentary sectional view of one wall of the engine cylinder and the head therefor separated.

Corresponding and like parts are referred to in the following description and indicated in all the views of the accompanying drawings by the same reference characters.

Referring to these drawings, 2 and 3 designate parallel cylinders of an internal combustion engine. These cylinders are of an ordinary construction, that is, they are closed at their upper ends by a head and are open at their lower ends. Each cylinder is formed with a water jacket as is also the head.

Preferably the head of each cylinder is detachable and is held in place by bolts. This is illustrated in Fig. 8 wherein the cylinder 2 is shown as being provided with a head 4 which rests upon the outwardly projecting flange 5 of the cylinder and is held thereto by a plurality of bolts 6 having set nuts 7. Each head is formed with a spark plug opening 8 and with an opening 9 screw threaded for engagement with a priming cock 9^a (see Fig. 1). Both cylinders are constructed in precisely the same manner and therefore a description of one applies to the other.

The cylinders are provided each at its lower end with an outwardly projecting flange bolted or otherwise attached to a crank case 10 and supported by the same.

It is not intended that the cylinders shall be removed from the crank case under normal circumstances but that if it is desired to clean the interior of the cylinder or do light work, it is only necessary to remove the head 4. Disposed within each cylinder is the usual piston 11 from which extends the piston rod 12 to the corresponding crank 13 of the crank shaft 14 which passes through and is mounted in bearings in the crank case. All these parts may be of any ordinary or usual construction, though as before remarked, the cylinder head is preferably removable for the purpose stated.

15 In the ordinary sliding valve sleeve type of engine, the valve sleeve is mounted within the explosion chamber and is hence subjected to the action of the hot gases. This tends to expand the valve sleeve and cause 20 it to bind so that it does not run smoothly. It also causes a great deal of friction and is inconvenient in other ways. For the purpose of obviating these objections, I provide a sleeve valve or valves mounted in a gas 25 chamber separate and distinct from the engine cylinder. Preferably I provide two gas and valve chambers, one for the exhaust valve and one for the inlet valve, the inlet valve chamber being connected to the inlet 30 ports of a plurality of cylinders, as for instance the inlet ports of the two cylinders illustrated and the other being the exhaust valve chamber and operatively connected to the exhaust ports of a plurality of cylinders, 35 as for instance the exhaust ports of the two cylinders illustrated. The construction of these valve chambers is illustrated in Fig. 2. Both of the valve chambers are constructed in precisely the same manner but one is 40 used for controlling the inlet of motive fluid and the other the exhaust. Therefore, the valve chambers and their allied parts will be distinguished from each other by exponents. Thus in Fig. 2, 15 designates the 45 inlet valve chamber and 15^a the exhaust valve chamber. Each chamber is cylindrical in form and has a uniform diameter from end to end and is preferably open at its upper end. Each chamber is surrounded by 50 a water jacket 16^a relatively large at its upper end as at 16.

Disposed within the exterior chamber 15 or 15^a is an inner sleeve 17 or 17^a. This inner sleeve is approximately the same in length 55 as the outer wall of the cylinder and forms the inner wall of the cylinder. This inner sleeve is preferably hollow so as to provide a water space 18 or 18^a. The inner sleeve 17 at its lower end rests upon the inner face of 60 the outer wall of the chamber and at its middle is held to the outer wall by means of a bolt 19 or 19^a. It will be seen that thus a cylinder is provided having an outer wall and an inner wall, both walls being formed 65 with water jackets or water spaces and the

outer face of the inner wall being spaced from the inner face of the outer wall so as to leave between the two walls a valve space 20 or 20^a. The inner sleeve or wall incloses a gas space. At its upper end the inner sleeve or wall 17 or 17^a is enlarged so as to form a head 21 or 21^a which fits snugly within and over the upper edge of the outer wall 15 or 15^a and which is held thereto by means of screws 22 which extend through the outer wall of the cylinder. Preferably each head 21 or 21^a is hollowed out as at 23 to form a lubricant chamber closed by a cap 24 having in its center an opening closed by a plug 25. The space 23 is connected to the upper 70 end of the space 20 by means of perforations 26. The manner in which lubricant is supplied to the chamber 23 and thence to the valve space 20 will be later described.

The inner wall of the valve chamber constituted by the members 17 and 17^a is illustrated in detail in Fig. 4 wherein the member 17 is shown, it being understood that the member 17^a forms a gas chamber, is precisely the same in form as member 17 and 80 that the ports of the member 17^a are arranged precisely the same as for the member 17. The inner wall 17 is closed at its bottom or lower end as at 27 and is provided at one side with a port 28 disposed opposite to a port 29 in the outer wall 15. The port 29 in the valve chamber 15 is connected to a pipe 30 leading from a carbureter, but the port 29^a of the cylinder 15^a is connected to a pipe or like duct 30^a leading 90 to a muffler.

The interior wall 17 of the cylinder 15 (and the interior wall 17^a of the cylinder 15^a) is also provided with ports 31 and 32 (or 31^a and 32^a). The ports 32 are disposed above the ports 31 and preferably there are four of these ports 32 and four of the ports 31 extending at spaced intervals around the member 17.

Disposed within the annular valve space 20 110 is a valve designated 33 for the cylinder 15 and 33^a for the cylinder 15^a. These valve sleeves 33 and 33^a are constructed in precisely the same fashion and have the same ports, these ports being arranged in the same relation. Therefore, a description of the valve cylinder 33 will apply to the valve sleeve 33^a.

The valve sleeve 33 is open at opposite ends and is provided with a port 34 (34^a in sleeve 33^a) which has a length equal to the stroke of the valve and which is adapted at all positions of the valve to register with the ports 28 and 29 (or 28^a or 29^a) so that the ports 28 or 29 (or 28^a or 29^a) are always open to permit the introduction of fluid from the carbureter (or to permit the exhaust of fluid from the exhaust valve chamber). The valve sleeve 33 is also provided with the ports 35 and 36, the valve sleeve 33^a being, 120 125 130

of course, provided with like ports 35^a and 36^a. These ports are disposed one above the other, the ports 36 being disposed near the upper end of the sleeve 33 and the ports 35 at an intermediate position. The ports 35 and 36 are arranged at spaced intervals around the valve sleeve. When the valve sleeve is in its lowered position, the ports 36 will register with the ports 32. When the 10 valve sleeve is in its raised position, the ports 35 will register with the ports 31.

The outer wall of the cylinder 15 is formed with a chamber 37 which opens into a duct 37^a leading to the cylinder 2 and the 15 outer wall is also provided with a chamber 38 which opens by means of a duct 38^a into the cylinder 3. Thus when the valve 33 is in its lowest position, the interior of the cylinder 15 will be in communication with the 20 explosion chamber 2. When, however, the valve is in its lowered position, the valve chamber will be in communication with the cylinder 3. Inasmuch as the valve chamber 15 is always in communication with a source 25 of fluid, it will be obvious that when a communication is established between said chamber and the cylinder 2, motive fluid will pass from the chamber into the cylinder and that when the valve chamber is in communication 30 with the chamber 3, motive fluid will pass from the chamber into the cylinder 3.

The valve 33^a is also provided with the ports 35^a and 36^a which are adapted to register respectively with chambers 37^b and 38^b 35 connecting by ducts 37^d, 38^d with the cylinders 2 and 3 respectively. Thus when the port 36^a is in register with the chamber 37^b, communication will be established between the valve chamber 15^a and the cylinder 3 and 40 when the valve 33^a is lowered, communication will be established between the explosion chamber or cylinder 2 and the valve chamber 15^a.

It will be obvious that when the valves 33 and 33^a are in an intermediate position, the 45 ports leading to the cylinders 2 and 3 will be closed and that this will occur at the time when the charge is being compressed and when it is being fired.

The lower end of each of the valves 33 and 33^a is transversely slotted as at 39 to permit a portion of the outer wall of each cylinder to be extended through this slot as 50 illustrated in Fig. 2 and disposed beneath the bottom of the inner wall of the valve chamber so that the water space 16^a of the outer wall may be connected to the water space 18 of the inner wall by means of ports 40 so as to secure a circulation of water 55 through the outer and through the inner walls. This applies to both valve chambers.

The lower end of each valve is formed 60 with a removable yoke 41 extending diametrically across the lower end of the valve and 65 provided with spaced downwardly extend-

ing ears 42 within which the valve rod is pivoted upon a bolt 43 or like member.

The oil reservoir 23 formed in the upper end of each of the inner walls of each valve chamber is preferably connected by a pipe 70 42' leading to a pump (not shown), which pump is operatively connected to the crank case so that the oil within the crank case may be forced upward through the pipe 42' and discharged into the reservoirs 23 and 75 20 so that lubricant is applied to the upper end of the valve space.

The lower end of each valve space 20 opens into the crank case. The lower ends 80 of the valve sleeves are lubricated by a splash from the crank case. Of course, the explosion cylinders are also lubricated by a splash feed from the crank case.

As before stated, the pistons in each of 85 the cylinders are connected by means of the piston rod 12 to the cranks 13 on the shaft 14 and for the purpose of reciprocating the valves in proper time to the reciprocations of the pistons, I provide lateral valve shafts, 90 one of which is illustrated in Fig. 1 and designated 44. Mounted upon the crank shaft is a gear wheel 45 and mounted upon each shaft 44 is a gear wheel 46 meshing with the gear wheel 45. The gear wheel 45 95 is one-half as large as the gear wheels 46 so that the shafts 44 will rotate one-half as fast as the crank shaft 14.

Pivotedly mounted between the ears 42 of each of the valves is a valve rod 47. This 100 valve rod at a point intermediate its ends is formed with a shoulder 48. The lower end of this rod terminates in what may be termed an eccentric ring 49 having internal cam faces formed by the inner edges of 105 webs 50. These cam faces have a peculiar configuration as will be later described.

Surrounding the rod 47 and disposed on each side of the shoulder 48 are the coil springs 51 and 52, both having the same 110 strength, and surrounding the coil springs and the rod 47 is a cylindrical casing 53 having ends 54 pierced for the passage of the rod 47. It will be understood that this case 53 is loose upon the rod 47 and movable 115 longitudinally with relation thereto and forms a section thereof. This casing 53 is preferably formed in two sections bolted to each other by bolts 55.

The lower end of the casing is provided 120 with oppositely disposed, parallel, downwardly extending legs 56 whose lower ends embrace and rotatably engage the cranked portion of the crank shaft 44 as illustrated in Fig. 5. It will therefore be seen that as 125 the crank shaft rotates, the casing 53 will be reciprocated vertically.

The springs 51 and 52 are relatively 130 strong and hence a reciprocation of the casing 53 will cause a reciprocation of the rod

47 and a reciprocation of the sleeve valve. It will be obvious, however, that the rod 47 is independently movable with relation to the casing in either direction against the 5 force of either the spring 51 or the spring 52. This independent movement of the rod 47 is secured by means of a cam 57 which is mounted upon the cranked portion of the crank shaft in a plane between the two 10 legs 56 and disposed in the same direction as the crank. Preferably the crank is slotted. The cam is inserted in this slot and is held in position by a transverse bolt 58. The cam is not intended to move independently of the crank shaft and extends radially from the center of motion of the crank 15 shaft.

The webs 50 which form part of the ring 49 are disposed, one above and one below 20 the crank shaft and the inner edge of each web is sinuously curved and is adapted to have the cam wipe thereagainst. As illustrated, the middle portion of each web is concavely rounded as at 59 in an arc of a 25 circle concentric with the arc upon which the cam 57 moves. On each side of this concavely cutaway portion 59 there are protuberant portions 60. As the cam rotates, as will be plain from the position of the 30 cam on the right hand side, Fig. 2, the cam will wipe against the first of these protuberant portions 60 and the eccentric will be lifted, lifting the rod 47. It will then remain stationary while the cam travels 35 from the crest of one protuberant portion to the crest of the opposite protuberant portion. As it passes the crest, the cam will move out of engagement with the cam faces 59, the eccentric will be lowered by the lowering of the legs 56 and will travel downward carrying with it, of course, the rod 47. The cam on the crank rotates until it 40 wipes against the lower web 50 engaging first with the protuberant portion 60 thereof 45 so as to positively depress the eccentric and the rod 47, then engaging the concave middle portion 59 thereof holding the valve rod steady, then again depressing the valve rod and then passing around so as to engage the 50 uppermost web 50 and lift the eccentric. It will thus be seen that I provide for two separate means for shifting the valve rod. In effect, the valve rod is telescopic and while one portion is moving in one direction, 55 the other portion is also shifted. It is by this means that I secure a proper throw of the valve with a relatively small throw of the crank.

With this construction as the crank shaft 60 rotates, the first action will be to lift the casing or sleeve 53 and this through the spring 52 bearing against the shoulder 48 will lift the rod 47 in the ordinary manner of crank motion. As the valve nears its 65 upper position, however, with the ports still

out of register with the ports in the walls of the valve chamber, the cam 57 will act as previously described to additionally shift the rod 47 and additionally move the valve sleeve to its proper position. In other words, 70 the action of the crank is to move the valve sleeve nearly to its full position, and the action of the cam is to bring the valve sleeve fully into its proper position and its ports in proper register with the ports of the valve 75 casing.

It will of course be noted from Fig. 2 that the casing 53 is formed at its middle portion with an inwardly extending flange 61 which when the cam 57 is directed downward registers with the flange 48 formed on the rod 47. Seated upon the upper and lower faces of this flange 61 are the washers 62 upon which the springs 51 and 52 bear. These washers 62 overlap both the faces of 85 the flange 61 and the opposite faces of the flange 48. Thus any upward movement of the rod 47 beyond its middle position independent of the casing 53 is resisted by the spring 51, the spring 52 remaining idle while 90 any downward movement of the rod 47 with relation to the casing is yieldingly resisted by the spring 52 without, however, affecting the spring 51.

Otherwise than as before stated, the operation of my invention is the same as that of any other internal combustion engine. The gas from the carburetor passes into the gas receiving chamber 15, thence passes alternately into one or the other of the connected working cylinders and the exhaust gases pass from the cylinders alternately into the exhaust gas valve chamber 15^a from whence they pass off into the muffler or any other suitable discharge. It is to be particularly noted that with this construction the internal valve sleeve 17 or 17^a may be readily removed by simply removing the bolts 22 and that when removed, this exposes the entire interior of the valve chamber. The valve rod 47 may be then disconnected from the valve sleeve and the valve sleeve removed entirely through the top of the valve chamber. Thus the valve may be easily repaired, replaced or adjusted, and the interior faces of the valve sleeves of the walls between which the valve sleeves operate may be cleaned if desired. 110

It is particularly pointed out that the valve construction is such that the valve rod 47 is disposed immediately beneath the axial center of the valve and not at one side of its axial center. Where the valve rod is at one side of the axial center, the action of the valve rod tends to cause the valve to bind within the valve space and not work smoothly. With my construction, this binding is obviated and inasmuch as the force is entirely axial, friction is very greatly reduced. I thus secure all the advantages of 115 120 125 130

the sleeve valve with none of the disadvantages due to overheating of the valve and binding of the parts.

What I claim is:

5. 1. An internal combustion engine including a combustion chamber, a valve chamber distant from the combustion chamber and having outer and inner walls spaced from each other, both said walls being jacketed to provide a water jacket on the exterior of the outer wall and the interior of the inner wall, said jackets extending the whole length of the walls, said outer and inner walls being formed to each provide an inlet port and a discharge port, one of said ports being connected to the combustion chamber, a reciprocating valve sleeve fitting in the space between said walls and having ports adapted to register with the ports of the valve chamber and to at times close the port connected to the combustion chamber while keeping the other port constantly open, and means for reciprocating the valve sleeve.
10. 2. In an internal combustion engine, a valve chamber including a casing open at one end, and closed at its opposite end and forming the outer wall of the valve chamber, a cylindrical member conterminous there-with and adapted to fit within the casing and form the inner wall of the valve chamber, said inner cylindrical member being closed at both ends and provided at its outer end with a head closing the outer end of the casing, and a valve disposed between said walls, the outer and inner wall and said valve being provided with coacting ports.
15. 3. In an internal combustion engine, a valve chamber having outer and inner walls spaced from each other to provide a valve space, a lubricant containing chamber formed in the head of said valve chamber and having ports leading into the end of the valve space, and a valve disposed in said space.
20. 4. In an internal combustion engine, a valve chamber comprising an outer casing forming the outer wall of said chamber and open at one end, a hollow cylindrical member disposed within the casing having an enlarged head at one end adapted to close the end of the casing, said cylindrical member having a lubricant containing chamber formed at its headed end having ports leading into the space between the outer and inner walls, and a valve disposed between said outer and inner walls, said valve and said walls being formed with coacting ports.
25. 5. In an internal combustion engine, a

valve chamber comprising an outer cylindrical casing open at one end and having a uniform bore, an inner cylindrical hollow member forming a gas containing chamber fitted within the casing to form the inner wall of the valve chamber, said member being formed with an enlarged hollow head at one end adapted to close the open end of the casing, a cap closing the hollow head, the head being provided with ports leading into the space between the outer and inner walls, and a valve disposed between the outer and inner walls.

6. In an internal combustion engine, a valve chamber comprising an outer cylindrical casing having a uniform internal diameter open at its outer end, a cylindrical member forming the inner wall of the casing and smaller in diameter than the casing, means for detachably connecting the inner end of the inner member to the inner end of the outer casing, a head on the outer end of the inner member closing the outer end of the outer casing, the inner member being formed with water spaces, forming a water jacket coextensive with the member, said outer casing and the inner member being both formed with a gas inlet port and a gas outlet port, a combustion chamber spaced from the outer casing, a duct leading from one of said ports to the combustion chamber, a water jacket entirely inclosing the combustion chamber, the duct and the valve chamber, and a valve sleeve operating between the outer and inner walls of the valve chamber and provided with ports coacting with the ports thereof.

7. In an internal combustion engine, a valve chamber comprising an outer cylindrical casing, said casing forming an outer wall of the valve chamber, an inner cylindrical member forming the inner wall of the casing, the outer and inner walls at their outer ends each having transversely extending webs and being connected to each other through said webs, and a valve sleeve operating between the outer and inner walls, the valve sleeve and said walls being provided with coacting ports, the valve sleeve at its lower end being formed with oppositely disposed slots for the passage of the transverse web of the outer wall.

In testimony whereof I affix my signature in presence of two witnesses.
